(57) **CLAIM**

We claim the ornamental design for a sport helmet, as shown and described.

DESCRIPTION

FIG. 1 is a perspective view of a sport helmet (with environmental features shown in broken lines);

FIG. 2 is a side view of the sport helmet, the opposite view being a mirror image thereof;

FIG. 3 is a front view of the sport helmet;

FIG. 4 is a rear view of the sport helmet;

FIG. 5 is a top view of the sport helmet; and,

FIG. 6 is a bottom view of the sport helmet.

The details shown in broken lines are for illustrative purposes only and form no part of the claimed design.
